UNITED STATES PATENT OFFICE

108,547

DESIGN FOR A SHOE EYELET

Sahatiel G. Mandalian, North Attleboro, Mass.

Application August 19, 1937, Serial No. 71,187

Term of patent 7 years

To all whom it may concern:

Be it known that I, Sahatiel G. Mandalian, a citizen of the United States, residing at North Attleboro, in the county of Bristol and State of Massachusetts, have invented a new, original, and ornamental Design for a Shoe Eyelet, of which the following is a specification.

In the accompanying drawing which forms a part of this specification;

Figures 1, 2 and 3 are a top plan view, a bottom plan view and a side view respectively of a shoe eyelet embodying my invention, and

Figure 4, a section of the same on line 4—4 of Figure 2.

The characteristic features of my design reside in the substantially triangular form of the eyelet top having rounded corners; in the slightly elevated relation of the inner or bead portion of the top relatively to the remainder or border portion of the top; in the curved lateral edges of the clamping lugs; and in the fact that the upper surface of the border portion of the top is of a color contrasting with the bead portion of the top.

I claim:

The ornamental design for a shoe eyelet, as shown and described.

SAHATIEL G. MANDALIAN.
